OPHTHALMIC MOUNTING

Edward M. Splaine, Southbridge, Mass., assignor to American Optical Company, Southbridge, Mass., a voluntary association of Massachusetts

Original application January 15, 1936, Serial No. 59,247. Divided and this application December 20, 1937, Serial No. 180,787. In Canada October 18, 1935

2 Claims. (Cl. 88—47)

This invention relates to improvements in ophthalmic mountings and has particular reference to improved lens holding means.

This application is a division of my co-pending application, Serial #59,247, filed January 15, 1936.

One of the principal objects of the invention is to provide an improved lens holding means that will resiliently ease off the rigidity in the connection of the holding means to the lens, that will insure said holding means returning to its initial aligned position after such easing off, that will provide means for controlling the tension of the resilient means during use, that will maintain the connection of the holding means to the lens firm and substantially rigid to prevent looseness and play during the use of the mounting and yet be of such a nature as to relieve shock and strain on the lenses when the glasses are dropped or roughly handled and that will eliminate the exactness and accurateness in the fitting of the parts to be connected usually required in mountings of this character in the past.

Another object is to provide a novel arrangement whereby the resilient means is spot welded to the lens holding means.

Another object is to provide novel means functioning separately of the lens face engaging portion of the lens holding means for attaching the resilient means to said lens holding means and for preventing twisting of said resilient means sidewise relative to said lens holding means during use.

Another object is to provide resilient means with relatively straight transversely extending end portions whereby the said resilient means will have substantially line contact with each other and with the lens at their respective ends.

Other objects and advantages of the invention will become apparent from the following description taken in connection with the accompanying drawing and it will be understood that many changes may be made in the arrangement of parts, and details of construction shown and described without departing from the spirit of the invention as set forth in the accompanying claims. I, therefore, do not wish to be limited to the exact arrangement of parts, and details of construction shown and described as the preferred form only has been given by way of illustration.

Referring to the drawing:

Fig. I is a fragmentary front elevation of an ophthalmic mounting embodying the invention;

Fig. II is an enlarged fragmentary perspective

view of the strap or lens holding means shown in Fig. I; and

Fig. III is a sectional view of the lens strap or holding means shown in Fig. II.

Much difficulty has been encountered in the past in fitting and securing the resilient means to the lens strap or lens holding means so that the said resilient means will be positively held in proper aligned relation with each other and in secured relation with the lens strap or holding means during use. It, therefore, is one of the primary objects of this invention to obviate the above defects by providing a construction securing the resilient means to the lens holding means so that the said resilient means and lens holding means will be in integral relations with each other and will permanently retain said aligned integral relation with each other.

Referring more particularly to the drawings wherein like characters of reference designate like parts throughout the several views, the improved lens holding means or strap 1 embodying the invention as shown in Figures I to III inclusive, comprises a portion 2, which when viewed from the front is relatively straight, and has a temple connection 3 adjacent one end thereof and a bifurcated portion 4 adjacent its opposite end. The bifurcations of the portion 4 are adapted to engage with the front and rear surfaces of the lens 5 and are provided with openings aligned with an opening in the lens through which attaching means 1, such as a screw or other suitable means known in the art, is extended.

The lens holding means 1 is provided with resilient means 8 of a plurality of sections 9, 10 and 11 of varying lengths which extend outwardly of both sides of the lens holding means and provide relatively long free acting resilient means having no backing shoe in engagement with the rear thereof for limiting their movement. The resilient means is secured to the portion 2 overlying the edge of the lens by spot welding which is accomplished by the provision of a suitable apparatus of the conventional type having a contact engaging the springs in the vicinity wherein the welding operation is to be performed. In this particular instance the welding is performed at a point 18 intermediate the ends of the resilient sections 9, 10, and 11. This welding integrally joins the sections with each other and with the overlying portion 2 of the lens holding means.

Care is taken before the welding operation is performed, to carefully align the spring sections with each other and support the said sections in proper relation with the portion 2 to which they

are to be welded. The contact of the welding apparatus is then placed in engagement with the resilient means at the point at which the said welding is to take place. The contact is then 5 pressed into engagement with the resilient means and the welding operation completed by directing a hot shot of electric current through the welding apparatus and aligned resilient means and portion 2 with which the said resilient means 10 are to be secured.

The connecting means 7 may be of the prior art solder connected pivoted type by which a controlled pivotal action may be obtained and more or less permanently maintained during the 15 use of the device. This type of pivotal connection in combination with the resilient means set forth above enables the forming of a free acting integral pivotal connection which is limited in pivotal movement in both directions by 20 the resilient shock and strain absorbing means.

From the foregoing description it will be seen that I have provided simple, efficient and economical means of obtaining all of the objects and advantages of the invention, particularly that of 25 providing novel means integrally securing the resilient means to the lens holding means so as to permanently secure the parts in proper aligned and fitted relation with each other.

The resilient sections 9, 10, and 11 are each 30 provided with transversely extending flat ends 12, 13, and 14 as shown in Fig. II. The said sections 9, 10 and 11 may also be provided with the same or different degrees of resiliency. It is also to be noted that the upper and lower 35 edges 15 and 16 of the portion 2 are also straight and extend transversely of the resilient section 9. Said relatively straight transversely extending edges 15 and 16 and ends 12, 13 and 14 of the resilient sections provide substantial line 40 contact with each other and aid in preventing the said sections from tending to twist sidewise to cause the said welded connection at the point 18 to be under strain during the flexing of said resilient means.

It is also to be understood that the resilient means 17 at the bridge connection to the lens 45 is generally similar to the construction of the lens strap or lens holding means 1.

Although the construction has shown three 50 superimposed resilient members it is to be understood that one, two or more of said resilient members may be used as desired.

The welded connection 18 positively holds the resilient sections in fixed relation with the lens holding means so that there is no working at 55 said connection which will tend to cause the said sections to separate from the lens holding means during use.

The construction is such that the parts may be 60 quickly and easily assembled and that a relatively inexpensive and durable construction is obtained.

Having described my invention I claim:

1. In a device of the character described for 65 attachment to a lens, said device comprising a

lens holding member having a portion shaped to overlie the edge of the lens and a portion shaped to overlie a face of the lens and be secured to said lens, said portion shaped to overlie the edge of the lens normally having a continuous uninterrupted attachment surface of a width in the direction of the edge of the lens substantially no greater than the widest part of the portion overlying the face of the lens, and a plurality of superimposed blade-like resilient 10 members of varying lengths each normally having continuous imperforate surfaces adapted to be positioned to overlie the edge of the lens and each having a portion intermediate the ends thereof overlying the attachment surface of the portion of the lens holding means shaped to overlie the edge of the lens and spot welded in integral surface to surface relation with each other and to said normally uninterrupted attachment surface, said resilient members extending outwardly of the opposite sides of said edge portion with the longest spring adapted to engage the edge of the lens being free to flex throughout the major portion thereof during use and being adapted to engage the edge of the lens 15 in a direction extending peripherally along said edge when the lens holding member is in connected relation with said lens, the respective opposed ends of each of said resilient members being free to flex with respect to the spot welded 20 portions thereof during use.

2. An ophthalmic mounting comprising a pair of lenses, lens holding means attached to said lenses, said lens holding means comprising a portion overlying a face of the lens and secured to said lens and a portion overlying the edge of the lens, said portion overlying the edge of the lens having a continuous attachment surface of a width in the direction of the edge of the lens substantially no greater than the widest part of the portion overlying the face of the lens and a plurality of blade-like resilient members of varying lengths with imperforate portions intermediate the ends thereof overlying the attachment surface of the portion of the lens holding means shaped to overlie the edge of the lens and spot welded to said attachment surface so that the said intermediate portions of the resilient members are integrally joined in surface to surface relation with each other and in surface to surface relation with the portion of the lens holding means overlying the edge of the lens, said resilient members extending outwardly of the opposite sides of said edge portion with the longest spring adapted to engage the edge of the lens being free to flex throughout the major portion of its length during use and engaging the edge of the lens on said sides in a direction extending peripherally along said edge with the respective opposed ends of each of said resilient members being free to flex with respect to the spot welded portions thereof during use.

EDWARD M. SPLAINE.
